(57) **CLAIM**

The ornamental design for a “rolling tool crib and work bench,” as shown and described.

DESCRIPTION

FIG. 1 is a perspective view of a rolling tool crib and work bench, showing my new design;

FIG. 2 is a right side elevation view thereof, the left side elevation view being a mirror image thereof;

FIG. 3 is a rear elevational view thereof;

FIG. 4 is a front elevational view thereof;

FIG. 5 is a top plan view thereof; and,

FIG. 6 is a bottom plan view thereof.
